UNITED STATES PATENT OFFICE.

JOHN H. THOMAS, OF SPRINGFIELD, OHIO.

TEDDER-FORK.

SPECIFICATION forming part of Letters Patent No. 329,242, dated October 27, 1885.

Application filed October 17, 1884. Serial No. 145,775. (No model.)

To all whom it may concern:

Be it known that I, JOHN H. THOMAS, of Springfield, county of Clark, and State of Ohio, have invented a new and useful Improvement 5 in Tedder-Forks, of which the following is a full, clear, and exact description, reference being had to the accompanying drawings, making part of this specification.

This invention relates to certain new and 10 useful improvements in tedder-forks; and it has for its objects, first, to provide a tedder-fork of such construction that the same may yield to obstructions to such an extent as to fully and entirely overcome the same, and yet 15 which can be returned to normal position under the influence of a spring; and, second, to provide a clip for securing a spring to the tedder-arm in an adjustable manner.

In the accompanying drawings, forming a 20 part of this specification, and on which like reference-letters indicate corresponding parts, Figure 1 represents a rear elevation of my improved tedder fork and clip as applied to a tedder-arm; Fig. 2, a partial side elevation and 25 a partial sectional view of the same, and Fig. 3 a detached perspective view showing the interior construction of the spring-clip.

Letter A designates a tedder-arm of any 30 approved type, being preferably constructed of a straight bar of wood. To the lower end of this arm are connected metallic plates B, one at either side, which extend rearwardly some distance, and are held to the arm by means of one or more bolts. The rear ends of said plates are 35 provided with apertures and with lugs F, whose function is to limit the oscillation of the forks when the same yield to an obstruction.

The letter C designates the tedder-forks, which are constructed of a single piece of wire, 40 and bent so as to form the tines or fork-prongs proper, as well as the horizontal portions which fit within the apertures b of the plates B. From the latter points the fork extends upwardly and forwardly, and thence transversely, so as 45 to constitute a U-shaped portion. The object in providing the fork with the U-shaped portion is to give the spring (presently to be described) control over the movement of the fork, and the object of extending the U-shaped 50 portion toward the front of the machine is to secure the contact of the spring with the U-

shaped portion at a point, a line drawn from which to the points of the fork will pass to the forward side of bearings b of the fork. The result of this construction is to allow the forks 55 to yield to obstructions and rise so high from the ground at their points as to accomplish every possible practical requirement in respect to passing over obstructions of maximum size, and yet always cause the point of contact 60 between the spring, already mentioned, and the U-shaped portion to be so far above the bearings of the fork in the ends of the plates B that the pressure of the spring will uniformly and without failure return the fork to normal po- 65 sition.

I would here observe that it has come to my knowledge that tedder-forks have heretofore been pivotally mounted and provided with a U-shaped portion, with which a spring is adapt- 70 ed to come in contact and return the fork to operative position when thrown out of that position by an obstruction; but in such instance the fork cannot be raised a sufficient distance above the ground to pass over obstructions met 75 with in some sections of the country without causing the point of contact between the U-shaped portion and the spring to pass so far below the bearings of the fork in the plates B as to cause the action of the spring to hold the 80 forks in this abnormal position rather than to bring their points down by pressing against the U-shaped portion. This defect arises from the fact that in the instance alluded to the position of the U-shaped portion with respect to 85 the tines or prongs is such that a right line drawn from the center of the U-shaped portion to the points of the fork will intercept the pivotal axis of the fork. An anti-friction roller, D, is mounted upon the transverse part of the 90 U-shaped portion, so as to reduce friction and avoid wear between the spring E and said part.

F represent shoulders formed upon the lugs B B, preferably, upon their inner side, as shown, for limiting the throw or forward move- 95 ment of the fork C in yielding to obstructions.

In tedder-forks in common use, and as generally constructed, the spring E is curved its entire length, which also increases the amount of resistance and wear of parts. I prefer to flatten or straighten the said spring out toward its lower end, as shown, or where it passes over

the crank or **U**-shaped portion, and is acted upon thereby, this configuration allowing the roller to move more freely, which is desirable.

As an improved means for securing the 5 spring E to the fork-arm A, and at the same time rendering it capable of adjustment, I employ a flanged metal casting or clip, G. (Shown in detail in Fig. 3.) It is provided with flanges g g, which embrace the fork-arm A, extending 10 upon either side thereof and of the spring, and serving to steady the latter and keep it in place, and give strength to the casing to withstand the movement of the spring.

The interior of clip G is made flaring or 15 in form corresponding approximately to the curvature of spring E, which is secured therein. The adjustment of spring E is obtained by the employment of a set-screw, I, passing through the clip G, and bearing with its inner 20 end against the outer face of the spring. By the turning of the set-screw I the spring may be depressed in order to regulate the tension thereof or to compensate for wear or the loss of power from use. The same bolt H which 25 secures the clip G to the fork-arm may also be employed to secure the crank-wrist bearing or box (indicated at J) to the same arm A, but upon the opposite side thereof.

Having now described my invention, I claim 30 as new—

1. The combination, with the fork-arm, of the retaining-clip, made flaring upon its inner

face to accommodate the spring, and means, substantially as described, for adjusting the tension or pressure of the spring.

2. The combination, with the fork-arm, of the pivoted fork provided with the **U**-shaped portion or crank-arm, the spring acting on said crank-arm, the clip for securing said spring to the fork-arm, and the set-screw connected therewith, substantially as described, for adjusting the spring.

3. In a hay-tedder, the combination, with the tedder-arm, of the spring secured thereto, and a tedder-fork pivotally mounted in bearings located at the rear of said arm, and provided with a **U**-shaped bend at its upper end, against which said spring bears, and which is extended forward of the axis of the fork, so as to bring the axial line in the rear of a line drawn from the fork-points to the center of the cross portion of said bend, whereby the relative position of the cross portion and the axial line is such that the fork can be thrown a greater distance above the ground, and the spring still be capable of bringing the fork back to operative position.

In testimony whereof I have hereunto set my hand this 13th day of October, A. D. 1884.

JOHN H. THOMAS.
